UNITED STATES PATENT OFFICE.

CLARENCE H. PLUMMER, OF KEWAUNEE, WISCONSIN.

PEA-VINER.

1,269,211.

Specification of Letters Patent. Patented June 11, 1918.

Application filed May 29, 1916. Serial No. 100,432.

To all whom it may concern:

Be it known that I, CLARENCE H. PLUMMER, a citizen of the United States, residing at the city of Kewaunee, county of Kewaunee, and State of Wisconsin, have invented new and useful Improvements in Pea-Viners, of which the following is a specification.

My invention relates to improvements in 10 machines for shelling and removing green peas from their pods and vines.

The practice heretofore has been to place the pods and vines within a rotary drum along which they are fed longitudinally and 15 repeatedly lifted by the rotation of the drum and dropped into the path of an interior set of beating wings, whereby the peas are separated from the pods by impact of the wings upon the pods while the latter are in mid air. These machines have been quite successful in breaking or splitting the pods without crushing the peas, but it has been found that after the peas have been separated from the pods, a considerable number of the free 20 peas will be carried around and again subjected to the beating operation, and these peas frequently become crushed against the vines and pods and also against the walls of the drum to which they are thrown by the 25 beaters.

Attempts have been made to overcome this difficulty by perforating the walls of the drum in order to allow the free peas to escape, but this has only partially overcome 30 the difficulty, for the reason that many of the peas are entrained in the pods and vines and fail to reach the perforations or openings in the walls of the drum before being again elevated and subjected to one or more 35 additional beating operations. For this reason, it has heretofore been found impossible to avoid crushing, breaking or bruising a considerable percentage of the peas.

The object of the present invention, therefore, is to provide means whereby the pods and vines are subjected to repeated shaking operations after each beating operation and under conditions whereby the free peas are not only shaken out from the other material, 45 but are allowed to drop by gravity upon an inclined surface down which they are permitted to roll freely to the exterior, the remaining material being again elevated and redelivered to the beaters.

50 A further object of my invention is to pro-

vide means whereby impacts of the free peas upon the surfaces against which they are thrown when initially separated from the pods, may be reduced to a minimum, the surfaces against which they are thrown being comparatively soft and adapted to yield under such impacts.

In the drawings—

Figure 1 is a vertical section, drawn on line 1—1 of Fig. 2. 60

Fig. 2 is a vertical section, drawn on line 2—2 of Fig. 1. 65

Fig. 3 is a horizontal section, drawn on line 3—3 of Fig. 1.

Like parts are identified by the same reference characters throughout the several views. 70

The material, *i. e.*, the pea vines, including the unopened pods, is fed into one end of the machine from the platform 1, as best shown in Fig. 2. This material is received upon a set of interior feeding bars 2, the upper surfaces of which are serrated and adapted to feed the material rearwardly when the bars are reciprocated, as herein-after explained. The material is delivered by these bars to the lower end portion of an elevator or elevating conveyer, comprising an endless belt or apron 3, provided with flights or vine lifting members 4, which are adapted to engage the material and carry it upwardly. The material thus elevated passes between the apron and an angular shield or plate 8, the upper portion of which projects forwardly. The conveyer apron 75 also travels along this portion of the shield and the material is then supported by the shield and scraped along the shield by the apron until it reaches the upper margin of the shield, whereupon it is permitted to drop into the path of a set of beating wings 5 rigidly mounted upon a revoluble drum 6, said drum being revolved with sufficient rapidity to cause the wings 5 to strike the material in rapid succession while the latter is in mid air. The impacts delivered by the wings 5 upon the pods, breaks them open and releases the peas. The beating action of the wings 5 will of course 80 tend to throw the material toward the upper and front portion of the machine. Each of the wings has a slight angular pitch, whereby the material is not only thrown forwardly, but is also fed longitudinally toward the outlet end of the machine. The forward 85

110

movement of the vines is checked by a longitudinal series of fingers 11, depending from the upper portion of the frame and whereby the vines are again directed downwardly 5 into the path of the beater wings. The shelled peas, however, are permitted to pass between these fingers.

The fingers may be composed of flexible material, whereby the peas will not be split 10 or broken upon striking them. They are also narrow and are so spaced that the shelled peas may easily pass between them, while the motion of the vines and the pods is arrested. The peas passing between the 15 fingers 11 are permitted to strike upon the non metallic and preferably flexible wall 9, which may be composed of canvas, secured at intervals to the frame 19 of the machine. The vines and pods which are thrown by 20 the beater wings 5 in front of the fingers 11, are received upon another set of shaking fingers 12 which project inwardly through openings in the canvas wall of the machine with a downward inclination in the direction 25 of the beater. These fingers are vibrated, preferably in a vertical plane, whereby the dropping peas are shaken out from the other material and allowed to pass through between the fingers and downwardly to an inclined apron conveyer 6. This conveyer extends inwardly and upwardly from the front of the machine, and the upper surface of the apron travels in the direction indicated by the arrow in Fig. 35 1. The inclination, however, is sufficient to permit the peas to roll downwardly to the lower end of the apron and drop into a receiver 7. Fragments of vine and pods which drop to this apron will be carried upwardly and rearwardly and delivered over the rear end of the conveyer to the elevating conveyer 8.

The shelled peas dropping through the spaces between the fingers 12 may be directed toward the front side of the machine 45 by a segmental shield or guide 25, the upper margin of which is capped by a longitudinally extending roller 26 actuated in the direction indicated by the arrow in Fig. 50 1, the object of the roller 26 being to prevent vines or fragments of vines from lodging on the upper margin of the shield 25. The peas which pass in front of the shield 25 between it and the front wall or canvas covering of the drum, are thus protected from the beater wings, but the vines and pods which do not pass through between the fingers 12 are redelivered to the beater wings and are carried downwardly between the 55 beater drum and the shield 25 and thrown upon third and fourth sets of fingers 13 and 14 respectively, these fingers being also vibrated. The fingers 12, 13 and 14 are pivotally supported from the frame by pivot 60 shafts 12', 13', and 14', to which the fingers

are rigidly secured. Each of these pivot shafts or rods 12', 13' and 14' is provided with a rearwardly projecting arm 40, through which motion is transmitted to vibrate the fingers from an actuating shaft 70 41, provided with eccentrics 15, one of which transmits motion to the upper arm 40 and vibrating fingers 12 through the connecting rod 19, whereas the other eccentric transmits motion through connecting rod 20 and 75 its extension 21 to the lower arms 40 pertaining to the vibrating fingers 13 and 14 respectively. The fingers 13 and 14 are downwardly and forwardly inclined and adapted to slowly feed the material forwardly and redeliver it to the shaking bars 2 after repeatedly shaking the material to facilitate the escape of the shelled peas therefrom.

Owing to the fact that the fingers 13 are nearly horizontal and the movement of the material slow, there is a tendency for the juice or sap escaping from the broken vines and pods to cause an accumulation on these fingers, or fragments of fiber, pieces of pods 80 and dirt which tend to clog and fill the spaces between the fingers and eventually prevent the passage of peas between them. To overcome this tendency, I employ a comb 43 carried upon a set of revolving 95 chains 44, which travel over supporting pulleys or sprocket wheels 45. This comb extends longitudinally of the machine and the fingers or prongs thereof project upwardly between the fingers 13, whereby accumulations of material are scraped or combed out from between said fingers. In the construction shown, the carrier chains 44 support only one comb. This will ordinarily be sufficient even though the chains 100 44 may be slowly driven, since the accumulations of material on the fingers are not very rapid. It is desirable that the chains and comb be placed in as close proximity to the shaking fingers 13 as is practical in 110 order that short combing fingers may be used. In order to avoid interference with the vibratory movements of the fingers 13 in case the comb should be in a position registering with the inner or rear ends of 115 the fingers during the downward movement of the latter, the inner or rear shaft 45 may be yieldingly supported. This, however, is not strictly necessary as the chains will ordinarily not be tight enough to prevent the 120 comb from yielding.

It will of course be understood that the material redelivered from the fingers 13 and 14 or thrown by the beaters 5 to the shaking bars 2, will be shaken by these bars and redelivered to the elevating conveyer 3, whereby the material is again lifted along the rear side of the machine and again delivered into the path of the beating wings 125 from above the upper margin of the shield 130.

8. But owing to the fact that the beater wings 5 have an angular pitch, adapted to feed the material longitudinally, it is obvious that the material thus redelivered from 5 the elevator 3 will be received by the beater wings at a point more distant from the inlet end of the machine than the freshly delivered material, so that the operation of feeding fresh material into the machine may be 10 continuous and each successive beating operation carried on without interfering with any other beating operations, each successive beating or shelling operation being performed nearer to the vine outlet than the 15 preceding one, the vine outlet B being located at the end of the machine opposite that having the inlet adjacent to the platform 1.

The shaking bars 2 are actuated from the 20 shaft 29 through the eccentrics 30 and connecting rods 30'. These shaking bars 2 are preferably actuated in alternation. The front ends of the bars are adapted to slide upon a supporting rod 31. The connecting 25 rods 30' are rigidly connected with the rear ends of the bars respectively, whereby these ends of the bars travel in a circular path. The bars are therefore adapted to not only feed the material rearwardly but also co- 30 operate with the shaking fingers in agitating the material and separating the shelled peas therefrom.

The endless apron 3 of the elevating conveyer has its margins supported by end 35 rollers 36 around which the apron travels in the form of an endless belt. Marginal guide rollers 34 and 35 determine the path along which the apron travels on its front or working side and guide rollers 36' are 40 employed to determine the path of the apron on the rear or return side. The guide rollers 34 and 35 are so disposed that the receiving portion of the apron 3 between these rollers is upwardly and rearwardly inclined, 45 whereas the portion above the roller 35 inclines forwardly and is substantially parallel to the upper portion of the shield 8.

The actuating connections whereby the machine is operated, are not illustrated in 50 the drawings. These connections may be of any ordinary construction. Preferably motion is communicated from a suitable source of power to the drum supporting shaft 37 and from this shaft to the other moving 55 parts of the machine by ordinary belts, chains or gearing.

Briefly reviewing the operation of the machine, it will be understood that the material is fed into one end of the machine 60 from the platform 1, delivered by the shaking bars 2 to the elevating conveyer 3, from which it is permitted to drop into the path of the beating wings, after which it is beaten, thrown by the beating wings and 65 redelivered thereto successively from the fin-

gers 11 and 12, and then thrown to the fingers 13 and 14, which redelivers it to the shaking bars 2 at a point longitudinally distant from the inlet. These bars redeliver the residue of the material to the elevating 70 conveyer 3 and the series of beating operations is thereupon repeated, the free peas being removed after each beating operation, as above explained, and allowed to drop to the apron 6, down which they roll to the 75 exterior at the front of the machine. The front of the machine is entirely open below the shaking fingers 13, whereby the peas are permitted to freely escape downwardly and forwardly. The drum 6 may have flexible 80 or non metallic walls, whereby any peas which strike the drum will escape injury. In the ordinary machines, these walls are frequently perforate, comprising an open screen or mesh. I do not, however, limit 85 the scope of my invention to any specific features of the drum, and I desire to be understood as designating the various parts of my machine merely for the purpose of description, the terms and designations employed not being used for the purpose of limitation, as it is not my intention to exclude from the scope of my invention any mechanical equivalents for the features of 90 invention disclosed.

I claim—

1. A pea viner, comprising the combination with a drum having peripheral beaters, of a belt elevator at one side of the drum, adapted to repeatedly lift and drop material into the path of the beaters, and means for shaking the material to separate shelled peas from the other material after each beating operation and preparatory to the next lifting operation.

2. In a pea viner wherein separation of the peas from the pods is effected by impact upon the pods while the latter are falling in free air, the combination with the means for imparting pea shelling impacts to the pods and vines, of an elevator for lifting and returning them to the impact mechanism for reshelling operations, and means, independent of the impact mechanism, for shaking the pods and vines after each impact thereon to remove the peas as fast as they are shelled.

3. In a pea viner, the combination of devices for beating pods and vines while dropping by gravity in free air, means for successively lifting the pods and vines while outside of the range of the beating devices and dropping them repeatedly into the path of said beating devices, and separate means for agitating the pods and vines and shaking out the free peas after each dropping operation and preparatory to a succeeding lifting and dropping operation.

4. In a pea viner, the combination of a rotary member provided with projecting

- 4
- beater wings, means for elevating pods and vines and dropping them into the path of the beater wings, and agitators adapted to receive pods and vines thrown by the beater wings, and adapted to shake out the shelled peas; said agitators being adapted to re-deliver said pods and vines into the path of the beater wings.
5. In a pea viner, the combination of a rotary member provided with projecting beater wings and a belt elevator located along one side thereof and adapted to elevate vines and pods and drop them into the path of the beater wings, together with means for returning the vines and pods to the elevator after each set of beating operations until substantially all the peas are shelled, and an inclined support down which the peas are permitted to roll from the machine as soon as separated.
- 10 6. In a pea viner, the combination of a rotary member provided with projecting beater wings and an elevator located along one side thereof and adapted to elevate vines and pods and drop them into the path of the beating wings, together with means for shaking and returning the vines and pods to the elevator, until substantially all the peas are shelled, and means for allowing the shelled peas to escape from the machine after each beating operation.
- 15 7. In a pea viner, the combination of a rotary member provided with projecting beater wings and an elevator located along one side thereof and adapted to elevate vines and pods and drop them into the path of the beater wings, together with means for returning the vines and pods to the elevator after each beating operation, until substantially all the peas are shelled, means, located out of the path of the beaters for shaking the vines and pods, and means for directing the shelled peas away from the elevating and beating mechanisms during the shaking process, whereby the vines and pods may be returned to the elevator, independently of the shelled peas.
- 20 8. In a pea viner, the combination of a revoluble drum, an annular series of beater blades attached to said drum, means for revolving said drum and series of blades at a speed sufficient to shell peas by impact, an endless conveyer provided with a plurality of lifting members, said conveyer extending upwardly along the side and partially over said revoluble drum, and means for conveying pea vines and pods to said conveyer, said beater being adapted to strike the pea vines and pods in mid air as the latter are delivered from said conveyer, and means, independent of the beater, for separating and delivering the shelled peas to the exterior of said machine, as soon as they are shelled.
- 25 9. In a pea viner, the combination of vine dropping apparatus, vine beating apparatus and vine shaking apparatus, said vine shaking apparatus being arranged to receive the vines from the beating apparatus and return the same to the dropping apparatus after shaking out the shelled peas and said beating apparatus being arranged to operate upon the dropping vines to impart impacts thereto while the vines are entirely free to move with the beating devices.
- 30 10. In a pea viner, the combination with beater mechanism, of a series of shaking fingers adapted to shake the vines and pods as they pass from the beater mechanism, means for allowing the shelled peas to pass from the machine as fast as they become shelled, said shaking means being adapted to return the vines and pods to the beating mechanism and drop them by gravity into the path of the beaters for a reshelling operation.
- 35 11. In a pea viner the combination of an endless apron, means for retaining pea vines against the lower side the endless apron preparatory to dropping the same, whereby such vines are struck in mid air by a revolving series of beaters, and means for removing the shelled peas from the machine as fast as they are removed from their pods, and vines.
- 40 12. In a pea viner, the combination with shelling apparatus, of an inclined endless apron conveyer upon which shelled peas are free to drop and roll from the machine to the exterior, vine shaking apparatus interposed between the shelling apparatus and said apron, a pair of angular shafts for supporting the respective ends of said endless apron, said angular shafts being adapted to simultaneously shake said apron as the latter is being moved forward over said shafts, and said conveyer being actuated to feed the fragments of vines and pods thereon toward the receiving portion of the viner.
- 45 13. In a pea viner, the combination with a beater inclosing frame, of mechanism adapted to operate wholly by impact upon the vines and pods, a plurality of shaking fingers, a revoluble shaft, eccentrics connected with said shaft, and means for communicating motion from said eccentrics to said shaking fingers, whereby the pea vines are shaken as they are delivered from said beating mechanism, and means for automatically returning the vines to the beating mechanism after each shaking operation.
- 50 14. In a pea viner, the combination of devices for successively beating the pods and vines while dropping by gravity in free air, and vibratory means for agitating the pods and vines and removing the free peas therefrom in the intervals between said dropping operations.
- 55 15. In a pea viner, the combination of devices for beating the pods and vines while dropping by gravity in free air, vibratory

agitating devices adapted to receive the pods and vines delivered from the beating devices and arranged to shake out the free peas therefrom, and means for automatically 5 delivering the pods and vines into the path of the beating devices for a rebeating operation.

Copies of this patent may be obtained for five cents each, by addressing the "Commissioner of Patents, Washington, D. C."

In testimony whereof I affix my signature in the presence of two witnesses.
